UNITED STATES PATENT OFFICE.

ROBERT C. HALL, OF TITUSVILLE, PENNSYLVANIA.

NUT CRACKER AND PICK.

SPECIFICATION forming part of Letters Patent No. 512,818, dated January 16, 1894.

Application filed April 22, 1893. Serial No. 471,380. (No model.)

To all whom it may concern:

Be it known that I, ROBERT C. HALL, a citizen of the United States, and a resident of Titusville, county of Crawford, and State of Pennsylvania, have invented certain new and useful Improvements in Nut Crackers and Picks, of which the following is a specification, the principle of the invention being herein explained and the best mode in which 5 I have contemplated applying that principle so as to distinguish it from other inventions. The annexed drawings and the following description set forth in detail one mechanical form embodying the invention; such detail construction being but one of various mechanical forms in which the principle of the 10 invention may be used.

In said annexed drawings—Figure I represents a perspective view of my improved nut 15 cracker and pick; Fig. II, a plan view of the same, and Fig. III, a plan view of the device, illustrating its handles as swung around opposite to the direction illustrated in Figs. I and II, and thus illustrating the device as 20 ready for convenient storing away or transportation.

The jaws A, and handles A', are of the construction found in the commonly used nut crackers, and are pivoted in the usual manner to the fulcrum piece B, the general construction of which is like the ordinary nut cracker. Instead, however, of having the ordinary tongue at one end,—opposite to the 25 smaller tongue b,—a nut pick, B', is formed at that end of the fulcrum piece, so that the handles of the nut cracker proper, may be held as a handle for the pick.

The manner of using the nut cracker is exactly like the ordinary nut cracker and, whenever the nut cracker and pick is not used, the 40 handles may be reversed or swung around to have the pick projecting between them, whereby the pick is protected from either causing or receiving damage.

Other modes of applying the principle of 45 my invention may be employed for the mode herein explained. Change may therefore be made as regards the mechanism thus disclosed, provided the principles of construction set forth respectively in the following claims 50 are employed.

I therefore particularly point out and distinctly claim as my invention—

1. A nut cracker and pick having jaws and handles, and a fulcrum piece to which the 55 jaws and handles are pivoted at the ends of the jaws,—one of said members having a pick projecting beyond the pivot joint when the jaws and handles are turned in one direction, and folding between the jaws and handles 60 when the latter are reversed, substantially as set forth.

2. A nutcracker and pick consisting of jaws and handles and a fulcrum piece to which said jaws and handles are pivoted,—said fulcrum 65 piece having a pick projecting from one end, substantially as set forth.

In testimony that I claim the foregoing to be my invention I have hereunto set my hand this 25th day of February, A. D. 1893.

ROBERT C. HALL.
